UNITED STATES PATENT OFFICE.

GEORGE R. LUM, OF NEW YORK, N. Y., ASSIGNOR TO WESTERN ELECTRIC COMPANY, INCORPORATED, OF NEW YORK, N. Y., A CORPORATION OF NEW YORK.

DESIGN FOR A CASING FOR A TELEPHONE TRANSMITTER.

Application filed October 3, 1922. Serial No. 3,874. Term of patent 14 years.

To all whom it may concern:

Be it known that I, GEORGE R. LUM, a citizen of the United States, residing at New York city, in the county of New York and State of New York, have invented a new, original, and ornamental Design for a Casing for a Telephone Transmitter, of which the following is a specification, reference being had to the accompanying drawing, forming a part thereof.

Fig. 1 is a side view and Fig. 2 a front view of a telephone transmitter casing showing my new design.

I claim:

The ornamental design for a casing for a telephone transmitter, as shown.

In witness whereof, I hereunto subscribe my name this 26th day of September, 1922.

GEORGE R. LUM.
